UNITED STATES PATENT OFFICE

CHARLES C. COHEE, OF INDIANAPOLIS, INDIANA

DEVICE FOR REDUCING CARBON MONOXIDE IN HYDROCARBON ENGINES

Application filed January 13, 1930. Serial No. 420,602.

The incomplete combustion of carbon in the explosion of gasoline vapors in hydrocarbon explosion engines produces carbon monoxide (CO) which, because it combines with the haemoglobin of the blood of animals expelling the oxygen, is very poisonous. However, the carbon monoxide burns readily forming carbon-dioxide (CO₂) which can be breathed with immunity, and the principal object of the invention is to reduce the formation of the poisonous monoxide by producing a more complete combustion of all of the carbon.

Another object is to make the motor function better, with less consumption of gasoline, and at less expense per mile of travel because of the more perfect combustion of the carbon.

A further object is to provide a convenient vehicle for the introduction of lubricants to the interior rubbing parts of the engine and an additional object is to utilize a minimum quantity of water in the generation of steam by the heat in the exhaust manifold and so supply the steam to the air intake that a maximum amount of oxygen will enter the carburetor.

I accomplish the above and other objects which will hereinafter appear by the means illustrated in the accompanying drawing, in which—

Fig. 1 is a side elevation of a portion of the exhaust manifold of an automobile and a carburetor, with my invention assembled therewith, parts being broken away and in vertical section, the view being largely diagrammatic; and

Fig. 2 is a cross section on the line 2—2 of Fig. 1.

The exhaust manifold 3 and the carburetor 4 are of any usual and suitable construction. The wall of the manifold 3 is bored through and threaded.

A cylinder 5, as of wrought iron, has a longitudinal bore 6, entering from one end, but instead of extending entirely therethrough, the opposite end is left solid, as shown. The solid end of the cylinder is inserted through the threaded hole in the manifold where it is retained by screw threads 7,

formed externally on the cylinder which engage with the threads of the hole. The walls of the cylinder are provided with the small holes 8. An hexagonal flange 9 formed on the cylinder is for the application of a wrench in screwing the cylinder in or out of the manifold.

Threads 10 are formed on the cylinder above the flange 9.

A balloon shaped steam dome 11 of brass or other suitable metal, fits over the outer end of the cylinder 5. It has a contracted internally threaded end which screws on the threads 10 of the cylinder, making a steam tight fit therewith. An externally and internally screw-threaded nipple 12 is screwed into a threaded hole in the top of the dome. A pipe 13 is screwed into the nipple and extends down into the bore of cylinder 5, not into contact with, but near the inner end of the bore 6 thereof. The pipe is centered in the cylinder 5 by a collar 14.

The nipple 12 extends for a suitable distance outside of the dome 11, and to this extension a water supply pipe 15 is secured. The pipe 15 has a valve, here shown as a needle valve 16, by which the amount of water supplied through pipe 15 is regulated.

A pipe 17 is connected with the interior of the dome and the other open end of the pipe terminates opposite the open end of the air-intake pipe 18 of the carburetor 4. It is here shown as terminating inside of an air strainer 19 of usual form, but an air strainer is not an essential part of my invention. Attention however, is called to the fact that the pipe 17 discharges in front of the mouth and not inside of the air-intake pipe 18.

The dome may stand vertically as shown in Fig. 1, or horizontally or otherwise as conditions require, and it is provided with an opening for the discharge of water of condensation, or for steam, should the pressure within the dome become too great. This is normally closed by a ball valve 20. An opening at the greatest diameter of the dome normally closed by a plug 21, is provided for use when the dome is positioned horizontally.

In the operation of my invention water is

admitted by properly manipulating the valve 16, so that it is discharged in drops from the open end of pipe 13, upon the closed end of the cylinder 5. This end being solid for a considerable extent and heated by the hot gases discharging through the exhaust manifold, turns the drops of water into steam which steam discharges into the dome through the holes 8, and the steam discharges through pipe 17 to a point in front of the carbureter air-intake pipe 18, where it is drawn into the carbureter along with plenty of air to more thoroughly consume the carbon when the mixture is exploded in the cylinders of the engine.

Formation of carbon-monoxide is thus prevented and by reason of the more perfect combustion the efficiency of the engine is increased. In incomplete combustion of a hydrocarbon and air mixture, gases other than carbon monoxide are given off which are very nauseating and even poisonous. The introduction of the moisture into the combustible mixture has, in effect, a catalytic action, and by its presence causes a more perfect combustion of the mixture thereby eliminating the other objectionable gases in addition to the carbon monoxide.

I claim:

- 30 1. In a hydrocarbon explosion engine, an exhaust manifold and a carbureter having an air intake in combination with a steam generator comprising a member extended into the manifold and into a steam dome, an inlet pipe projecting into the member with means to cause water to drip into the member, a steam dome around the outlet from the generator and a conduit between the dome and the air inlet.
- 40 2. In a hydrocarbon explosion engine, an exhaust manifold and a carbureter having an air intake in combination with a steam generator comprising a hollow member extended into the manifold and into a steam dome, an inlet pipe projecting into the hollow member with means including a needle valve to cause water to drop into the member, a steam dome around the outlet from the generator and a conduit between the dome and air inlet.
- 50 3. In a hydrocarbon explosion engine, an exhaust manifold and a carbureter having an air intake in combination with a steam generator comprising a hollow member extended into the manifold and into a steam dome, an inlet pipe projecting into the hollow member with means including a needle valve to cause water to drop into the member, a steam dome around the outlet from the generator, a conduit between the dome and air inlet and a water drain from the steam dome.

In testimony whereof I affix my signature.
CHARLES C. COHEE.
